Inventor
John T. Mabee,
Barrett & Munroe,
Attorneys

UNITED STATES PATENT OFFICE.

JOHN T. MABEE, OF CHICAGO, ILLINOIS, ASSIGNOR TO RAYMOND BROS. ENGINEERING CO., OF CHICAGO, ILLINOIS, A CORPORATION OF ILLINOIS.

MEANS FOR BURNING LIME.

Application filed April 3, 1924. Serial No. 703,943.

My invention relates to means for burning lime, and it has for its principal object the provision of a new and improved form and arrangement of parts, by which a standard upright, stationary lime kiln can be fired by the use of pulverized fuel. In firing a kiln of this type by the use of pulverized fuel, it is necessary that the organization and arrangement be such that there shall be very little, if any slag carried into the kiln proper, and it has been the particular object of my invention to provide such an arrangement of parts. By my improved construction, by which I have succeeded in preventing the entrance of slag into the kiln proper, I have prevented the discoloration of the lime which would be effected by the slag if permitted to mix with the rock in the kiln.

Another important feature of my invention pertains to the maintenance of the draft through the kiln. In a construction of this sort, in which the draft must be maintained directly through the body of the mass of materials forming the contents of the structure, which in this case is in the form of broken lime rock, it is essential that the interstices between the pieces of rock shall not be filled either by the complete crumbling of the pieces, or in any other manner as by the entrance of some foreign material. When a standard upright kiln is filled for starting its operation, it requires the maintenance of a fire for a period of from three or four days up to eight or ten days, or even longer, before the contents of the kiln is brought to the condition justifying the first "draw" of lime. During this preliminary firing for bringing the kiln into production, it is particularly difficult to maintain the draft through the kiln, and it has been one of the special objects of my invention to provide a construction by the use of which this preliminary firing can be successfully effected by the use of pulverized fuel.

It is another object of my invention to improve devices of this type in sundry details, hereinafter pointed out. The preferred means by which I have accomplished my objects are illustrated in the drawings and are hereinafter specifically described. That which I believe to be new and desire to cover by Letters Patent is set forth in the claims.

In the drawings,

Fig. 1 is a front view of my improved kiln, partly broken away.

Fig. 2 is a horizontal sectional view through the kiln, being taken substantially at line 2—2 of Fig. 1.

Fig. 3 is a vertical section taken at line 3—3 of Fig. 2; and

Fig. 4 is a vertical section taken at line 4—4 of Fig. 2.

Referring to the several figures of the drawings, in which corresponding parts are indicated by the same reference characters, 10 indicates a kiln, the body of which is in the form of a vertically disposed shell, the bottom portion of which is oval, as is clearly shown in Fig. 2. The kiln comprises a combustion chamber 11, at each side of the body of the kiln, at its lower portion, such combustion chambers being preferably built with and incorporated as part of the kiln proper. As is clearly indicated in Fig. 3, each of the combustion chambers is preferably provided with a lining of fire-brick as is usual in such constructions. In the construction shown, the wall of the kiln is thickened and extended laterally at each side of each of the combustion chambers for providing a foundation 12 for the kiln. As will be readily understood, the body of the kiln ordinarily extends upwardly a distance of from 30 to 50 feet, being provided with means at the upper end for feeding the lime rock to the body of the kiln. Inasmuch as this feeding means forms no part of the present invention, it is not believed to be necessary to show it herein. At the bottom, the body of the kiln opens into a hopper 13, of any suitable type, as is shown in Fig. 4, for drawing the completed product from the kiln, the hopper being below the level of the combustion chambers.

As is best shown in Fig. 4, each of the combustion chambers is provided with means for feeding pulverized fuel thereto through the medium of a stream of air or other gas from any suitable source, such means comprising a nozzle 14 extending through a sleeve 15 opening downwardly into the combustion chamber. As is readily understood in the operation of devices of this type, the

stream of gas and fuel entering through the nozzle 14 causes, by induction, the entrance of auxiliary air through the sleeve 15 about the nozzle. A lighting port 16 is provided through the wall of the combustion chamber a short distance below the nozzle 14, as is best shown in Fig. 4.

In my improved construction, communication is afforded between the combustion chambers 11 and the body of the kiln by means of eyes 17, four of such eyes being provided between each combustion chamber and the body of the kiln. In the construction shown, these eyes are arranged in pairs, one pair being above the other pair, one eye of each pair being located directly above the corresponding eye of the other pair. It is not believed that this particular arrangement of the eyes is essential, but I do believe that it is important that the eyes be arranged at different levels, at least one eye being arranged above the level of one or more of the other eyes.

In the front face of each of the combustion chambers, there is arranged a punch hole 18, the level of the punch hole 18 being between that of the upper eye 17 and that of the lower eye 17. By this arrangement, access is had to both of the eyes from the same punch hole 18. In the construction shown, I have also provided a number of air openings 19 for the admission of auxiliary air for insuring the complete combustion of the pulverized fuel. At the bottom of each combustion chamber, I have provided an ash door 20, which is to be utilized for cleaning out the combustion chambers. The lighting port 16, the punch hole 18, and the ash door 20 are preferably provided with closing means of any suitable type, as illustrated, while the air openings 19 are ordinarily closed by the insertion of a brick when it is desired to limit the admission of auxiliary air.

Additional punch holes have been provided in the wall of the body of the kiln between the combustion chambers 11. One of these punch holes is located above the level of the combustion chambers, as is shown in Fig. 4, being indicated by the numeral 21. The other punch hole is located at substantially the same level as that of the lower eyes 17, such lower punch hole being indicated by the numeral 22. These holes are preferably provided with closing means of any suitable type, as illustrated in the drawings. As will be readily understood, access is had to the upper eyes 17 through the punch holes 21, while access is had to the lower eyes 17 through the punch holes 22.

For assisting in keeping down the temperature within the combustion chambers, as hereinafter described, I have provided a pipe 23 extending into the combustion chamber

and connected with any suitable source of water or steam, being provided with a plurality of openings 24 in its upper face for spraying such water or steam upwardly into the flame within the combustion chamber. 70

In operation, the kiln is filled from the top with lime stone, in the usual manner; pulverized fuel is fed through the nozzles 14 from a suitable source, and the streams of fuel are ignited by the use of the ports 16. 75 The fire then is maintained in the combustion chambers, the kiln itself acting as the flue, the hot gases passing upwardly through the mass of materials in the kiln. At intervals, as may be necessary, the eyes are 80 cleared of any material which may have gathered there in such a way as to prevent passage of the hot gases into the body of the kiln. This punching out is preferably effected by the use of a bar through the 85 opening 18. At the end of from three to five days, or more, according to weather conditions and other circumstances, the conditions will be found to be correct for a draw of four or five tons of lime through 90 the hopper 13, the kiln, of course, being re-filled from the top to replace the material withdrawn.

I have found in practice in the use of my improved structure and operation, that after 95 the kiln is brought into production, it is unnecessary to punch out the eyes 17 other than at the times of the successive draws of lime at intervals of three and one-half to six hours. This is very different from the 100 necessity in connection with a hand fired kiln, provided with the old form of eyes where it has been necessary ordinarily to punch out the eyes at intervals of an hour to insure the desired freedom of passage of 105 the flame through the eyes and the production of the desired draft through the combustion chambers.

It sometimes happens that when the line is withdrawn at the bottom of the kiln, 110 there is a tendency for the material to stick along the walls at a higher point. In view of this, I have provided the punch holes 21 for providing access to the interior of the kiln for enabling a worker to loosen the 115 material by the use of a bar. These punch holes 21 can also be used for access to the inner ends of the eyes 17.

In my improved construction, the combustion chambers 11 are proportioned so as 120 to insure the production of a large volume of mellow heat therein rather than a small volume of intense heat. This is of very considerable importance from the standpoint of maintenance of the lining of the 125 kiln and of the combustion chambers, but it is of even greater importance with respect to the formation of liquid slag. I have found in practice that by the use of a comparatively much larger combustion 130

chamber than those formerly used, I am enabled with the use of pulverized fuel to maintain the desired large volume of mellow heat for effective operation of the kiln without the formation of liquid slag. I have found that by the use of pulverized fuel for firing a kiln provided with my improved construction, I am enabled to produce from 20 to 30 or 40% more lime than could be done in the same kiln by hand firing before my improvements were installed. I have found that through the medium of the large volume of mellow heat produced by the use of my improved construction, the slag is not liquefied and it is a comparatively easy matter to keep the eyes cleared. Moreover, there is no difficulty under such circumstances about maintaining the desired draft, since the slag is not carried into the body of the kiln, but is deposited at the bottom of the combustion chamber in the form of small particles of ash or in the form of an easily broken honeycomb or sponge. This feature is of utmost importance in the operation of the kiln.

For the purpose of assisting in keeping down the temperature within the combustion chamber for freezing the slag particles and for maintaining the desired large volume of mellow heat, water or steam is preferably sprayed from the pipe 23.

So far as I am aware, I am the first in the art to provide an arrangement of parts by the use of which a stationary kiln of the upright standard type shown can be fired successfully with pulverized fuel so as to maintain continuously the required freedom of draft through the material in the kiln and so as to prevent the discoloration of the lime by slag passing into the body of the kiln. Inasmuch as these features are essential to a really successful operation of a kiln by the use of pulverized fuel, which I have accomplished by my improved construction comprising my novel arrangements of the eyes 17, and comprising the provision of a combustion chamber so proportioned and arranged as to insure the production of a large volume of mellow heat so as to prevent the formation of liquid slag, I desire to claim broadly the constructions by which these results have been attained, and my claims are to be construed accordingly.

By the use of my improved construction, by which the use of pulverized fuel is made successful, the health and comfort conditions of the workmen are wonderfully improved. In the use of the standard kiln of this type by hand firing, the smoke at the top of the kiln, where the men work feeding in the stone and preparing for the feeding, is very often so dense that it is difficult or impossible to see the men from the ground

50 or 60 feet away. In the use of my improved construction with pulverized fuel, the hot gases emerging from the top of the kiln carry practically no ash or other foreign substance.

While I prefer to employ substantially the form of construction illustrated in the drawings, it will be understood that I do not desire to limit myself to the details of construction except so far as they are specifically claimed, inasmuch as it is evident that changes may well be made in the construction without departing from the spirit of my invention.

I claim:

1. The process of burning lime by the use of pulverized fuel, which comprises placing lime stone in a stationary kiln, burning the fuel in a comparatively large separate combustion chamber so as to produce a large volume of mellow heat in the combustion chamber, and conducting the heated gases into the kiln and through the interstices between the broken limestone fragments held therein.

2. The process of burning lime by the use of pulverized fuel, which comprises placing the lime stone in a stationary kiln, burning the fuel in a comparatively large separate combustion chamber so as to produce a large volume of mellow heat in the combustion chamber, introducing steam into the lower part of the combustion chamber for assisting in preventing the formation of liquid slag, and conducting the heated gases into the kiln and through the interstices between the broken limestone fragments held therein.

3. The process of burning lime by the use of pulverized fuel, which comprises placing the lime stone in a stationary kiln, burning the fuel in a comparatively large separate combustion chamber so as to produce a large volume of mellow heat in the combustion chamber, spraying steam against the flame at the lower part of the combustion chamber for assisting in preventing the formation of liquid slag, and conducting the heated gases into the kiln and through the interstices between the broken limestone fragments held therein.

4. A kiln for burning limestone comprising a vertically elongated chamber for holding the limestone and adapted to serve as a flue for products of combustion and slag collecting, a large combustion chamber at one side of the kiln chamber and in open communication therewith through a comparatively small opening, and means for feeding pulverized solid fuel into the combustion chamber at a position remote from the opening whereby substantially complete combustion of the pulverized fuel will take place in the combustion chamber with deposition of slag, and the heated gases will be

drawn out through the opening and between the limestone fragments by the flue action of the kiln chamber.

5. A kiln for burning limestone comprising a vertically elongated chamber for holding the limestone and adapted to serve as a flue for products of combustion, a large combustion and slag collecting chamber at one side of the kiln chamber and in open communication therewith through a plurality of comparatively small openings, and means for feeding pulverized solid fuel into the combustion chamber at a position remote from the openings whereby substantially complete combustion of the pulverized fuel will take place in the combustion chamber, and the heated gases will be drawn out through the openings and between the limestone fragments by the flue action of the kiln chamber.
- 10 6. A kiln for burning limestone comprising a vertically elongated chamber for holding the limestone and adapted to serve as a flue for products of combustion, a large combustion and slag collecting chamber at one side of the kiln chamber and in open communication therewith through a plurality of comparatively small openings, and means for feeding pulverized solid fuel into the combustion chamber at the top and at a place remote from the said openings 30 whereby substantially complete combustion of the pulverized fuel will take place in the combustion chamber, and the heated gases will be drawn out through the openings and between the limestone fragments by the flue 35 action of the kiln chamber, and means for spraying steam into the lower portion of the combustion chamber.

JOHN T. MABEE.

drawn out through the opening and between the limestone fragments by the flue action of the kiln chamber.

5. A kiln for burning limestone comprising a vertically elongated chamber for holding the limestone and adapted to serve as a flue for products of combustion, a large combustion and slag collecting chamber at one side of the kiln chamber and in open communication therewith through a plurality of comparatively small openings, and means for feeding pulverized solid fuel into the combustion chamber at a position remote from the openings whereby substantially complete combustion of the pulverized fuel will take place in the combustion chamber, and the heated gases will be drawn out through the openings and between the limestone fragments by the flue action of the kiln chamber.
- 10 6. A kiln for burning limestone comprising a vertically elongated chamber for holding the limestone and adapted to serve as a flue for products of combustion, a large combustion and slag collecting chamber at one side of the kiln chamber and in open communication therewith through a plurality of comparatively small openings, and means for feeding pulverized solid fuel into the combustion chamber at a position remote from the openings whereby substantially complete combustion of the pulverized fuel will take place in the combustion chamber, and the heated gases will be drawn out through the openings and between the limestone fragments by the flue action of the kiln chamber.
- 15 7. A kiln for burning limestone comprising a vertically elongated chamber for holding the limestone and adapted to serve as a flue for products of combustion, a large combustion and slag collecting chamber at one side of the kiln chamber and in open communication therewith through a plurality of comparatively small openings, and means for feeding pulverized solid fuel into the combustion chamber at a position remote from the openings whereby substantially complete combustion of the pulverized fuel will take place in the combustion chamber, and the heated gases will be drawn out through the openings and between the limestone fragments by the flue action of the kiln chamber.
- 20 8. A kiln for burning limestone comprising a vertically elongated chamber for holding the limestone and adapted to serve as a flue for products of combustion, a large combustion and slag collecting chamber at one side of the kiln chamber and in open communication therewith through a plurality of comparatively small openings, and means for feeding pulverized solid fuel into the combustion chamber at a position remote from the openings whereby substantially complete combustion of the pulverized fuel will take place in the combustion chamber, and the heated gases will be drawn out through the openings and between the limestone fragments by the flue action of the kiln chamber.

ing a vertically elongated chamber for holding the limestone and adapted to serve as a flue for products of combustion, a large combustion and slag collecting chamber at one side of the kiln chamber and in open communication therewith through a plurality of comparatively small openings, means for feeding pulverized solid fuel downwardly into the combustion chamber at the top and at a place remote from the said openings whereby substantially complete combustion of the pulverized fuel will take place in the combustion chamber, and the heated gases will be drawn out through the openings and between the limestone fragments by the flue action of the kiln chamber, and means for spraying steam into the lower portion of the combustion chamber.

JOHN T. MABEE.

Certificate of Correction.

It is hereby certified that in Letters Patent No. 1,586,318, granted May 25, 1926, upon the application of John T. Mabee, of Chicago, Illinois, for an improvement in "Means for Burning Lime," errors appear in the printed specification requiring correction as follows: Page 2, line 109, for the word "line" read *lime*; page 3, lines 120 and 121, claim 4, strike out the words "and slag collecting" and insert the same to follow after the word "combustion" line 121, same claim; and that the said Letters Patent should be read with these corrections therein that the same may conform to the record of the case in the Patent Office.

Signed and sealed this 22d day of June, A. D. 1926.

[SEAL.]

M. J. MOORE,
Acting Commissioner of Patents.
